[57] CLAIM

The ornamental design for a card-adapter for video game, as shown and described.

DESCRIPTION

FIG. 1 is a perspective view from the front, left, and top sides of a card-adapter for video game showing my design;

FIG. 2 is a front elevational view thereof;

FIG. 3 is a rear elevational view thereof;

FIG. 4 is a right side elevational view thereof; the left side elevational view is an image thereof;

FIG. 5 is a top plan view thereof; and,

FIG. 6 is a bottom plan view thereof.

The ribbon cable shown in fragmentary views is intended to show it's undetermined length.

FIG.1

FIG. 2

FIG. 3

FIG. 4

FIG.5

FIG.6
